HOLDER FOR CIGARETTES, ETC.

John W. Wyllie, Franklin, Mass.

Application June 14, 1939, Serial No. 279,160

3 Claims. (Cl. 312—47)

This invention relates to article holders and dispensers and more particularly to a holder or container for cigarettes which may be served, one at a time, in a manner hereinafter more specifically to be described.

In the drawing:

Fig. 1 is a view of the cigarette holder attached to a support, as to the dashboard of an automobile;

Fig. 2 is a view of the holder partly in section, dotted lines representing one of the parts in the process of being removed from the other or companion part;

Fig. 3 is a detached view of one of the parts or elements constituting the container; and

Fig. 4 is a corresponding view of the other or companion part, portions thereof being broken away to illustrate the operation.

The holder 1 is shown attached to a support 2, such as the dashboard of an automobile, as by a suction cup 3, which cup is attachable to the part 4 of the container in any convenient manner.

The part 4 may be stamped of sheet metal with turned flanges 5, 6 and 7, the flange 6 being discontinuous providing a recess 8. At the lower end of the part 4 is an extension 9 which terminates in a turned or rolled flange 10. The extension 9 terminates short of the width of the upper portion of the part 4 to permit exit of the cigarettes 11 at one end and entrance of a spring plunger 12 at the other end to contact the lowermost of the cigarettes in the container so as to cause an end of the said cigarette to be moved to the position illustrated in Fig. 1 where it may be readily removed from the container.

The other or companion part 13 of the container is also conveniently stamped out of sheet metal and is provided with a top flange 14, side flanges 15, 16, and a lower, curved flange 17, the latter acting as a seat for the cigarettes. The side flanges 15 and 16 are each turned over as at 18 and 19 in a right angular direction to retain the cigarettes in vertical alignment. The upper ends of the turned over portions 18 and 19 of the flanges 15 and 16 terminate short of the upper ends of the said flanges to provide an opening within which fresh cigarettes may be inserted in the portion 13 of the container. For this purpose, the said portion 13 of the container may be removed from the portion 4 by engaging the knob 20 and moving the part 13 of the container, as indicated by dotted lines in Fig. 2.

Upon separation of the part 13 of the contain-

er from the part 4, cigarettes may be inserted in the opening in the container, the said cigarettes dropping down to the position illustrated in Fig. 4. Thereafter the cover part 13 of the container may be reassembled with the base part 4, by causing the curved flange portion 17 to seat in the correspondingly curved, flanged portion 10 of the part 4, the seating then serving as a hinge to permit the swinging of the cover part 13 to the closed position indicated in Fig. 1. During this closing movement, the flange 14 snaps under the flange 7, the two flanges constituting a catch for retaining the cover and base parts, 13 and 14 respectively, of the container, in closed position. When the cover and base portions of the container are connected as illustrated in Fig. 1, the lower portions of the flanges 15 and 16 partially close the portion of the opening at either end of the container formed by reason of termination of the flanges 5 and 6, short of the flange 10, leaving only sufficient opening at either end to permit exit of the cigarettes 11 and reception of the end of the plunger 12.

To remove a cigarette, the spring plunger 12 may be pressed inwardly from the dotted line position illustrated in Fig. 1, to the full line position illustrated therein, which causes the opposite end of the lowermost cigarette to protrude as illustrated in Fig. 1. The plunger 12, as illustrated in Fig. 4, is conveniently made of spring metal and has a curved shank, soldered or otherwise, connected to the flange 15, the lower portion 21 of the plunger being turned substantially at right angles to the shank portion thereof and the tip end 22 of the turned end of the plunger being again turned downwardly at an angle, less than a right angle, with respect to the portion 21. The connected end of the plunger 12 seats within the recess 8. As illustrated in Fig. 4, movement of the plunger from the position illustrated in the full lines to the position illustrated in the dotted lines, causes the tip end 22 of the plunger to engage a cigarette and force the same to the right, the end of the cigarette then protruding beyond the opposite end, as more clearly illustrated in Fig. 1. While the plunger 12 is being moved from the position illustrated in full lines in Fig. 4 to the position illustrated in dotted lines therein, the tip end of the said plunger engages under the adjacent end of the cigarette and tends to lift the same which causes the cigarettes above to be agitated and properly rearranged in their relative position in the event that any one or more of the cigarettes are relatively misplaced in the con-

tainer. The upward movement of the lowermost cigarette, and the consequent agitation of the cigarettes thereabove, is occasioned by the less than right angular disposition of the tip end 22 of the plunger with respect to the turned portion 21 thereof, so that when the plunger is in the dotted line position, or in its innermost position, the tip end of the plunger tends to lift the adjacent end of the lowermost cigarette. Upon release of the plunger 12, the same moves outwardly to the position illustrated in Fig. 4, the lower portion of the flange 15, especially designated by the numeral 23, serving as a stop by engaging the tip end 22 of the plunger.

In the preceding description, certain of the parts have been specifically described for illustrative purposes only, there being no intention of limiting the invention other than as required by the limitations in the claims themselves. It is obvious that the construction of the containing members can be varied and made of different materials; furthermore, the form of plunger may be varied.

I claim:

1. A two-part metal container having a recess therein, one end of each part having interengaging curved portions for interengagement, the opposite portions thereof constructed for interlocking engagement, the construction being such that articles, such as cigarettes, may be inserted in the container to be maintained in vertical alignment, in combination with ejecting means projecting beyond the container and opposite the recess therein for engaging the lowermost of the cigarettes or other articles and causing the same to be partially removed from the

container so that the same may thereafter be readily removed from the container, the ejecting means being so constructed as to agitate the articles in the container.

5 2. A container having a recess therein, the construction being such that articles, such as cigarettes, may be inserted in the container to be maintained in vertical alignment, in combination with ejecting means projecting beyond the container and opposite the recess therein for engaging the lowermost of the cigarettes or other articles and causing the same to be partially removed from the container so that the same may thereafter be readily removed from the container, the ejecting means being so constructed as to agitate the articles in the container, by engaging underneath the next article to be ejected and while one of said articles is being moved to the position to be readily removed from the container.

15 3. A container having a recess therein, the construction being such that articles, such as cigarettes, may be inserted in the container to be maintained in vertical alignment, in combination with ejecting means projecting beyond the container and opposite the recess therein, said means comprising a one-piece spring element affixed to the container and for engaging the lowermost of the cigarettes or other articles and causing the same to be partially removed from the container so that the same may thereafter be readily removed from the container, the ejecting means being so constructed as to agitate the articles in the container.
